LASTING MACHINE

Ernest W. Stacey, Beverly, and Daniel Walker Hannable, Beverly Farms, Mass., assignors to United Shoe Machinery Corporation, Flemington, N. J., a corporation of New Jersey

Application December 1, 1949, Serial No. 130,494

25 Claims. (Cl. 12—1)

1

This invention relates to lasting machines, and particularly to a novel and improved machine for completely lasting a shoe, at its toe and heel ends and along its opposite sides, in one automatic operating cycle. However, it will be understood that certain features of the invention are of broader utility and not limited to use in a machine of the exact type herein disclosed or to use in connection with the lasting of a shoe around its entire periphery.

In the lasting of certain types of shoes, or the lasting of the platform covers of so-called platform or slip-lasting shoes, where the lasting margin of the stock is to be secured, in lasted position, to the bottom of the shoe by means of an adhesive, the amount of heightwise pull required to tension the stock is not very great. In fact, it has been found that a very satisfactory lasting job may be obtained by subjecting the stock being lasted to a frictional upwipe, for producing the heightwise tension, provided, however, that the lasting margin of the tensioned stock is immediately laid inwardly over, and firmly pressed against, the bottom of the shoe. Moreover, this principle of frictional tensioning, followed by overlaying and pressing, may be carried out by means of elements which are particularly adaptable for lasting the toe and heel ends, as well as the opposite sides, of a shoe in one complete operating cycle.

It is, therefore, an object of this invention to provide a novel and improved lasting machine embodying the aforementioned principles. With this object in view, the herein illustrated machine is provided, in addition to a support for a shoe on its last, with a plurality of different lasting units each including means for tensioning the stock being lasted, at a selected portion of the shoe, and wiping means for laying the lasting margin of the tensioned stock inwardly over, and for pressing said lasting margin against, the bottom of the shoe. More particularly, and in accordance with features of this invention, there are two pairs of these lasting units, the units of one pair being arranged to operate, respectively, at the toe and heel ends of the shoe, while the units of the other pair are arranged to operate at the opposite sides of the shoe, and the arrangement is such that these different pairs of units operate in a predetermined sequence to effect lasting of different portions of the shoe around its entire periphery. Conveniently, and in the herein illustrated machine, these lasting units are mounted on a table that is reciprocated relatively to the shoe support in time relation to movements of these units toward and away from positions in operative relation to a shoe carried by the support. It is to be understood, however, that in a broader aspect this invention is not limited to a machine for lasting

5 a shoe around its entire periphery. Instead, without departing from the spirit of the invention, one or the other of the two pairs of lasting units may be omitted, or rendered inoperative, if it is desired for any reason to last either the toe and heel portions or the opposite sides of shoes in a different manner, as, for example, by the use of metallic fastenings. In a like manner, either the toe unit or the heel unit may be omitted, or rendered inoperative, should it be desired to last the toe or the heel portions of the shoes in another machine.

10 The tensioning means of each of the aforementioned lasting units comprises a member conformable to the contour of the last, at a selected portion of the shoe, and is operable, upon movement relative to the last, to tension the stock being lasted in a direction heightwise of the last, while the wiping means of each unit is movable relatively to the tensioning member 15 for laying the lasting margin of the tensioned stock inwardly over, and for pressing the lasting margin against, the bottom of the shoe. More particularly, and in accordance with other features of the invention, the wiping means includes an inflatable member that is conformable with the marginal edge of the bottom of the shoe and, for the purpose of facilitating the overlaying and pressing actions of this member, 20 the machine is provided with means for initiating the inflatable member at a relatively low pressure during its overlaying action and thereafter at a higher pressure for pressing the lasting margin of the tensioned stock against the bottom of the shoe. With this arrangement, the lasting margin of the tensioned stock is laid inwardly over the bottom of the shoe by the action of the inflatable member while it is inflated at a 25 relatively low pressure. Hence, this member conforms very readily to the marginal edge of the bottom of the shoe and all danger of deforming or dislocating the shoe bottom member is avoided. However, after this overlaying action has been completed, the inflatable member is inflated at a higher pressure so that the lasting 30 margin of the stock is pressed very firmly against the bottom of the shoe. It will be apparent that this novel wiper construction is not limited to use with the particular kind of tensioning means 35 with which the herein illustrated machine is provided, but, on the contrary, is of broader utility for use in lasting machines generally, regardless of the nature of the tensioning means.

40 The above and other objects and features of 45 the invention will appear in the following detailed description of the embodiment thereof which is illustrated in the accompanying drawings and will be pointed out in the claims.

In the drawings,

50 Fig. 1 is a view in front elevation of a ma-

55

chine embodying the features of this invention;

Fig. 2 is a view in side elevation of a portion of the right-hand side of the machine shown in Fig. 1, at an enlarged scale;

Fig. 3 is a view similar to that of Fig. 2 but at a smaller scale and with certain parts broken away and others shown in section;

Figs. 4, 5 and 6 are views in front elevation of certain of the operating elements of the machine with some parts omitted and others shown in vertical section, illustrating different positions assumed by these elements during an operating cycle of the machine;

Fig. 7 is a view in vertical section of one of the operating elements of the machine;

Fig. 8 is a view similar to that of Fig. 7 showing the positions of the parts at another point in the operating cycle;

Figs. 9 and 10 are plan views of a portion of the operating element shown in Figs. 7 and 8, showing the positions of certain parts thereof at different points in the operating cycle;

Fig. 11 is a view in vertical section, taken at right angles to Fig. 1 and at a larger scale, showing other operating elements of the machine;

Fig. 12 is a plan view showing the operating elements of the machine;

Fig. 13 is a plan view similar to that of Fig. 12, but with parts broken away and in section, showing, in addition, certain mechanisms for operating the elements of the machine;

Fig. 14 is a plan view at an enlarged scale of two of the operating elements of the machine in the positions assumed during an intermediate point in the operating cycle;

Figs. 15 and 16 are plan and sectional views, respectively, of a portion of one of the operating elements shown in Fig. 14;

Fig. 17 is a diagrammatic view of the operating elements of the machine and the fluid-pressure-control system therefor;

Fig. 17a is a view in section of a fluid-pressure control valve; and

Figs. 18 and 19 are plan and side elevation views, respectively, of a part of the mechanical drive and control mechanisms forming part of the machine.

Referring to these drawings, the lasting machine therein illustrated has four operating elements, or units, one for lasting the heel end of a shoe, designated generally by the reference character A, a second unit B for lasting the toe end of the shoe; and two other similar units C and D for lasting the opposite sides of the shoe, see Figs. 12, 13 and 17. These units are mounted on a table T, which, at certain points in the operating cycle, is reciprocated in a vertical direction relatively to a frame F. The general location and arrangement of these operating units on the table and the manner in which the table is supported on the frame will be apparent from an inspection of Figs. 1 to 6, 12 and 17 of the drawings. Each of the four operating units comprises a flexible member, conformable to the contour of a last at a selected portion of the shoe, for tensioning the stock being lasted, as a result of heightwise movement relative to the last, and a member movable in a direction to wipe the lasting margin of the tensioned stock inwardly over the shoe bottom and operable, thereafter, to press the overwiped lasting margin against the bottom of the shoe. Conveniently, these units are arranged to operate in pairs and, in the herein illustrated machine, the arrangement is such that the toe and heel ends

of the shoe are lasted first by units A and B, after which the sides of the shoe are lasted by units C and D. However, if desired, this sequence may be reversed and the sides of the shoe lasted before the toe and the heel end. In either case, a complete operating cycle will include vertical reciprocating movements of the table, bodily movements of the units on the table toward and away from operative positions relative to the shoe being lasted, and inward and pressing movements of the wiping members.

Referring first to the table T, this consists of a plate 20 to the underside of which there are secured three smaller plates 22, 24 and 26, see Figs. 1, 3-6 and 11. Formed integrally with the plates 22 and 26, respectively, are a pair of downwardly extending plungers 28 and 30, while the plate 24 is provided with a boss 32 on its lower side, Fig. 3. A cross rod 34 is connected to the lower ends of the plungers 28 and 30 and carries a pair of downwardly extending plates 36 and 38, Fig. 3. The frame F is fabricated from a plurality of sheet metal members, welded together, including vertical posts 40, cross members 42 and 44, Figs. 1 and 3-6. The cross members 44 are formed so as to provide guideways for slidably supporting the plungers 28 and 30, and groups of tension springs 46, 48 are stretched between the plates 36 and 38 and one of the upper cross members 44. The cross rod 34 carries a roll 48 that is held against a cam 50 by the springs 46, Fig. 3. As will be apparent, when the cam 50 is rotated, the table will be reciprocated in a vertical direction in accordance with the shape of this cam.

Referring to Figs. 1 and 19, cam 50 is provided with a lift portion 52, a drop 54, lift 56, drop 58 and lift 60, and is mounted on a shaft 62. This shaft is journaled in a bearing block 64 and carries a bevel gear 66, Fig. 3. Formed integrally with the cam 50 is a spur gear 68 which meshes with a pinion 70. This pinion is driven through a reduction gearing 72, having an input pulley 74 and a clutch 76, Fig. 1. The pulley 74 is connected to a motor 78 by means of a belt 80, the motor being mounted on a support 82 which is hinged to the frame F, Figs. 1 and 3. The clutch 76 is operated by means of a yoke 84, Fig. 3, and a plunger 86 which is associated with the upper end of the frame F, see Figs. 2 and 4.

The yoke 84 is at all times urged in a direction to engage the clutch 76 by means of a spring 88, diagrammatically illustrated in Fig. 4. However, when the table is in its lowermost position the yoke is held in a position to disengage the clutch by means of a bell-crank lever 90 having a cam-shaped arm 92. The other arm 93 of this lever has an offset end 94 which is engaged by the extension 96 formed on a lever 98 which is pivoted on the table. A coil spring 95 holds the body portion of the lever 98 against the end of the plunger 86, outward movement of which is limited by means of a pin 97. When the plunger 86 is pushed inwardly, i. e., to the left as viewed in Fig. 4, the extension 96 will pass beyond the offset portion 94 thus permitting the lever 90 to rotate in a counterclockwise direction. The spring 88 will now move the yoke 84 in a direction to engage the clutch 76 and thus start rotation of the cam 50. As a result of this rotation of the cam 50, the table will be reciprocated in the following manner. First, the table will be elevated to its highest position, see Figs. 5 and 6, as the roll 48 follows down the rise 52 to the drop 54 on

the cam 50. Next, the table will be lowered, part way, as the roll rides up onto the rise 56. Then the table will be elevated, a second time, by the drop 58 and then lowered part way again as the roll 48 rides up the rise 60. Finally, the table will be brought down to its lowest position, Figs. 1 and 4, as the roll 48 rides up the rise 52, at which point the cam 50 comes to a stop in the following manner. When the table was first elevated, and after the plunger 86 was released, the spring 95 returned the levers 90 and 98 to the positions shown in Fig. 4. Hence, on the final descent of the table to its lowermost position, the yoke 84 will be returned to a position so as to disengage the clutch, by reason of the engagement therewith of the cam-shaped arm 92, thus bringing the cam 50 to a stop.

During the aforementioned vertical reciprocating movements of the table T, the units A, B, C and D are operated to effect the lasting of the shoe in a manner which will be explained below. In order to perform their lasting functions, these operating units must be moved toward and away from operative positions relative to the shoe. Before describing the mechanisms by means of which these movements of the units are effected, the manner in which the shoe being lasted is supported will be explained. As has been suggested above, the herein illustrated machine is particularly adapted for lasting the platform cover of a slip-lasted shoe comprising an upper U, sock lining S, cover, or wrapper, W, and a platform P, having a heel part H, assembled on a last or form L. Secured to, and rising above the table T, are a pair of arms 100, 102 connected at their upper ends by means of a rod 104, Figs. 4, 5 and 6. Mounted on, and depending from, this rod is a shoe-supporting bracket 106 which is provided on one side with a groove 108. The last, or form, L has an upstanding portion 110 from which there projects a post 112 of a size to fit snugly in the groove 108 and of a thickness slightly greater than the depth of this groove. The post 112 is firmly clamped against the bottom of the groove 108, to secure the last or form onto the bracket 106, by means of a clamping bar 114 and a pair of wing bolts 116. It should be pointed out that the last or form L shown in the drawings is of a novel construction, disclosed and claimed in application Serial No. 102,524, filed July 1, 1949, in the name of E. W. Stacey. However, it will be understood, if it is desired to adapt the herein illustrated machine for handling shoes assembled on conventional lasts, that the bracket 106 may readily be modified to accommodate and support conventional lasts.

Turning now to the mechanisms for moving the units A, B, C and D toward and away from a shoe supported on the bracket 106 in time relation to the vertical reciprocations of the table F, these movements are produced by means of a cam 120, Figs. 3, 7, 11 and 13. This cam is mounted on a shaft 122 which passes through the boss 32 on the plate 24 and is slidably but non-rotatably connected to a second shaft 124, Figs. 3 and 7. The shaft 124 is journaled in the bearing block 64 and carries a bevel gear 126 that meshes with the bevel gear 66, Fig. 3. The ratio of these two gears is 1:1 so that the cam 120 is rotated once for every revolution of the table-operating cam 50. The heel unit A and toe unit B are operated at the beginning of the operating cycle of the machine and the movements of these two units will be described first. The heel unit comprises a bracket 130 which is adjustably secured, by

means of a clamp bolt 132, to a pair of blocks 134, 136 that are slidably mounted on the table plate 20 along a path defined by a slot 138, Figs. 1 and 4-8. Similarly, the toe unit B comprises a bracket 140, adjustably secured, by means of a clamp bolt 142, to blocks 144, 146 that are slidably mounted on the plate 20 along a path defined by a slot 148. The clamp bolts 132 and 142 extend below the plate 20 where they are connected, respectively, by links 149, 151 to the slotted ends of levers 150, 152, pivotally mounted on the lower side of the plate 20, as is shown more clearly in Fig. 13. Also pivotally mounted on the lower side of the table plate 20 is a third lever 154 connected at its opposite ends by links 156, 158 to the levers 150, 152, respectively, and carrying a cam roll 160. The cam 120, which rotates in the direction of the arrow in Fig. 13, has a rise 121 of about 90° arcuate extent and a dwell 123 of about 270° extent. As will be apparent, when the rise 121 engages the roll 160, the toe and heel units will be moved toward and into engagement with the toe and heel ends of a shoe supported on the bracket 106, as illustrated in Fig. 6. Springs 162, 164 and 166 are provided for holding the roll 160 against the cam 120 and for effecting withdrawal of the toe and heel units when the dwell 123 comes into engagement with the roll 160.

Referring to Figs. 3 and 11, the side unit C comprises a bracket 170 which is adjustably secured, by means of a clamp bolt 172, to a pair of blocks 174, 176 that are slidably mounted on the table plate 20 along a path defined by a slot 178. In a like manner, the side unit D comprises a bracket 180 adjustably secured, by means of a clamp bolt 182, to a pair of blocks 184 and 186 that are slidably mounted on the plate 20 along a path defined by a slot 188. Extending downwardly from the blocks 176 and 186, respectively, are pins 179 and 189. Also pivotally mounted on the underside of the plate 20 are a pair of levers 190, 192 which are connected, respectively, to the pins 179 and 189 and to a pair of bell-crank levers 194, 196, see Fig. 13. These two bell-crank levers are connected together by a link 193 and to the levers 190, 192 by means of links 195 and 197. The link 193 carries a pin 199 that is engaged by one end of a lever 201, also pivoted on the lower surface of the plate 20 and carrying at its opposite end a cam roll 203. When the rise 121 on the cam 120 engages this roll, the two side units will be moved toward and held in engagement with a shoe supported on the bracket 106 as is illustrated in Fig. 11. A spring 202 is connected to the link 193 for holding the roll 203 against the cam 120 and for withdrawing the side units when the dwell 123 comes into engagement with the roll 203.

Turning now to a detail description of the four operating units A, B, C and D, the heel unit A will first be described with particular reference to Figs. 4-10, 12 and 13. Referring at the beginning to Figs. 7, 8 and 12, associated with the bracket member 130 is a sheet metal housing construction 300 having upper and lower walls 302, 304 and side walls 303. Received in the space between these walls are three sheet metal cups 306, 308 and 310 (Fig. 12). In these cups are sponge rubber filler blocks 311 which are connected on their outer faces by means of a flexible rubber band 312 having a tread surface, or operating face 314, Figs. 4 and 5. Connected to the cup 308 is a plunger 316 which extends out through the bracket 130. Carried by this plunger 316 is a wedge-shaped abutment 318 which engages

the rounded ends of a pair of equalizing levers 320, 322. These levers are pivoted on the housing 300 and pass through openings therein to engage the cups 306 and 310. A coil spring 324 normally holds the parts in the positions shown in Fig. 12, with the abutment block 318 engaging the bracket 130. Under these conditions the rubber band 312 assumes a shape substantially as shown in Fig. 12 and with a curve of a radius somewhat greater than that of the heel end of a shoe. Hence, when the unit A is moved to bring the band 12 into engagement with the heel end of a shoe, the spring 324 will yield thereby causing the levers 320, 322 to press the end blocks 311 in cups 306 and 310 inwardly so that the band 312 will conform to and snugly embrace the heel end of the shoe. Subsequently in the operating cycle, when the table 20 is moved downwardly, the stock being lasted will be wiped in a direction heightwise of the shoe and tensioned by frictional action of the tread face 314 of the flexible band 312 on the stock.

Beneath the housing 300, the bracket 130 is formed with a forwardly extending plate 330 having vertical flanges 332, 334. Slidable on the plate 330 are a pair of arcuate blocks 336, 338 which are hinged together and to a plunger 340 by means of a pin 342 which rides in a slot 344 formed in the plate 330 (Figs. 7, 8, 9 and 10). At their ends the blocks 336, 338 are provided with pins 346, 348, respectively, which ride in cam slots 350, 352 cut in the plate 330. When the plunger 340 is moved to the left, as viewed in Figs. 9 and 10, the blocks 336 and 338 will be swung toward each other by the action of the slots 350, 352 on the pins 346, 348 and to the extent determined by a stop pin 347, carried by the plunger 340, and a slot 349 in the block 336. Secured to the blocks 336, 338 is a wiper member comprising an elongated inflatable rubber bag 360. For moving the plunger 340 to operate the wiper 360, the plunger 340 is extended through the end fitting 362 of a cylinder 364, carried by the bracket 130, and is provided with a piston 366. A coil spring 368, interposed between the piston 366 and the end fitting 362, normally holds the parts in the positions shown in Fig. 10. Flexible air pipes *a* and *b* are connected to the cylinder 364 on the opposite sides of the piston 366 and a flexible air pipe *c* is connected to the inflatable wiper 360. As will be explained in more detail below, the wiper 360 is normally inflated at a relatively low air pressure of approximately six lbs. per square inch. After the wiper has been operated by the piston 366 to wipe the lasting margin of the tensioned stock inwardly over the heel end of the shoe, the air pressure is considerably increased for the purpose of pressing the lasting margin against the bottom of the shoe.

Referring to Figs. 4-6, 12 and 13, the toe unit "B" is constructed in exactly the same manner as the heel unit A. Thus a sheet metal housing 400, having upper and lower walls 402, 404 and a side wall 403, is associated with the bracket 140, Figs. 4-6. Received in the space between these walls are three sheet metal cups 406, 408 and 410 each containing a sponge rubber filler block 411, Fig. 12. These blocks are connected on their outer faces by means of a flexible rubber band 412 having a "tread face," or operating surface, 414, Figs. 4-6. Connected to the middle cup 408 is a plunger 416 that extends out through the bracket 140 and is provided with a wedge-shaped abutment 418. Bearing against this abutment are the rounded ends of a pair of equalizing levers 420,

422 that are pivoted on the housing 400. A coil spring 424 normally holds the parts in the positions shown in Fig. 12, the abutment 418 engaging the bracket 140. Under these conditions, the flexible band 412 will assume a shape substantially as shown in Fig. 12 and with a curve of a radius somewhat greater than that of the toe end of a shoe. However, when the unit "B" is moved so as to bring the band 412 into engagement with the toe end of the shoe, the spring 424 will yield, thereby causing arms 420, 422 to press the end blocks 411 inwardly so that the band 412 will conform to and snugly embrace the toe end of the shoe. Thereafter, when the table 20 is moved downwardly, the stock being lasted will be wiped in a direction heightwise of the shoe and tensioned by the frictional action of the tread face 414 of the band 412 on the stock.

Under the housing 400 the bracket 140 has a forwardly extending plate 430 provided with vertical flanges 432, 434, Fig. 13. Slidable on the plate 430 are a pair of arcuate blocks 436, 438 that are hinged together and to a plunger 440 by means of a pin 442 the lower end of which rides in a slot 444 formed in the plate 430, Figs. 4-6 and 13. At their other ends, the blocks 436, 438 are provided, respectively, with pins 446, 448 that ride in cam slots 450, 452, cut in the plate 430. When the plunger 440 is moved to the right, Figs. 4-6, 13, the blocks 436, 438 will be swung toward each other by the action of the slots 450, 452 on the pins 446, 448 and to the extent determined by a stop pin 447, carried by the plunger 440, and a slot 449 formed in the block 436. Secured to the blocks 436, 438 is a wiper member comprising an elongated, inflatable rubber bag 460, Figs. 4-6.

For moving the plunger 440 to operate the wiper 460, this plunger is extended through the end fitting 462 of a cylinder 464 carried by the bracket 140, and is provided with a piston 466, Fig. 4. A coil spring 468, interposed between the piston 466 and the end fitting 462, normally holds the parts in the positions shown in Figs. 4, 5, 12 and 13. Flexible air pipes *d* and *e* are connected to the cylinder 464 at the opposite ends of the piston 466 and a flexible air pipe *f* is connected to the inflatable wiper 460. As is the case with the heel wiper 360, the toe wiper 460 is normally inflated at a relatively low air pressure of approximately six lbs. per square inch. However, after the wiper 460 has been operated by the piston 466 to wipe the lasting margin of the tensioned stock inwardly over the toe end of a shoe, the air pressure is increased so as to cause the wiper 460 to press the lasting margin against the bottom of the shoe.

The side units C and D, which are associated respectively with the brackets 170 and 180, are of identical construction. Accordingly, and to avoid repetition, the following detailed description will be directed particularly to unit D, Figs. 1, 2, 3, 11, 12, 13 and 14. However, the corresponding elements of the other unit C will be identified with the same reference characters, increased by one hundred, so that the description will apply equally well to the other unit. Referring to Fig. 11, mounted on the bracket 180 (170) there is a sheet metal housing 500 (600) having top and bottom walls 502, 504 (602, 604) and side walls 503 (603). Received within the space between these walls are four sheet metal cups 506, 508, 510 and 512 (606, 608, 610, 612) having hollow back portions, as shown more particularly in Fig. 14. Fitted in each of these cups 515 is a sponge rubber filler block 511 (611) and these

four filler blocks are connected, on their outer faces, by means of a flexible rubber band 513 (613) having a "tread face," or operating surface 514 (614). This flexible band is loosely connected to the housing 500 (600) by means of leather straps 515, 515 (615, 615).

Bearing against the end cups 506 (606) and 512 (612) are the rounded ends of a pair of equalizing levers 520, 522 (620, 622) pivoted on the housing 500 (600). Secured to the inner two blocks 508, 510 (608, 610) are plungers 524, 526 (624, 626) carrying caps 528, 530 (628, 630) slideable thereon. Coil springs 532, 534 (632, 634) surrounding the rods 524, 526 (624, 626) normally hold these rods in the positions shown in Fig. 12 and as determined by stop collars 536, 538 (636, 638). Resting against the caps 528, 530 (628, 630) and also on collars 540, 542 (640, 642) are another set of coil springs 544, 546 (644, 646) which tend to hold the caps against two other collars 548, 550 (648, 650), also secured to the rods 524, 526 (624, 626). The levers 520, 522 (620, 622) are connected to the caps 528, 530 (628, 630) by means of links 527, 529 (627, 629). With this arrangement, the flexible band 513, and also the flexible band 613, normally assume the shapes shown in Fig. 12 which approximate the contours of the last at the sides of a shoe. However, when the units C and D are moved toward each other and so as to bring the flexible bands 513 and 613 into engagement with the sides of a shoe supported on the bracket 106, the springs 532, 534, 544, 546 and 632, 634, 644 and 646, will yield so as to permit the bands 513 and 613 to conform exactly to the contour of the opposite sides of the shoe as illustrated in Fig. 14. Thereafter, when the table 20 is moved downwardly, these flexible bands will wipe the lasting margin of the stock being lasted in a direction heightwise of the shoe and in this manner will tension the stock. The tread surfaces 514 and 614, formed on these flexible bands, increase the friction set up between these bands and the stock being lasted, thereby augmenting the tensioning action.

Beneath the housing 500 (600) there is a plate 552 (652) and on this plate a wiper block 553 (653) is slidably supported, Fig. 11. This wiper block is further supported by means of a pair of rods 554, 555 (654, 655) which pass through bearing bores 556, 557 (656, 657) formed in the bracket 180 (170), Fig. 15. Compression springs 559, 559, (659, 659) normally hold the wiper block in the position shown in Figs. 11, 15 and 16. The operating portion of the wiper comprises an inflatable rubber member 560 (660) that is secured to the block 553 (653) by means of plates 561 (661) and screws 562 (662), in the manner illustrated in Figs. 15 and 16. For operating the wiper 560 (660) a pair of air cylinders 564, 564 (664, 664) are provided. Pistons 565, 565 (665, 665) arranged in these cylinders, have piston rods 566, 566, (666, 666) which extend through bearing bosses 567, 567 (667, 667) formed on the bracket 180 (170) and engage the block 553 (653) Fig. 15. An air pipe *k*, a portion of which is flexible, is connected to the ends of the cylinders 564, 564, behind the pistons 565, 565 and a pipe *l*, also having a flexible portion, is connected to a port 570 in the block 553 which leads into the space behind the inflatable wiper member 560. The pipe *l* passes through a clearance hole 572 in the bracket member 180 so as to partake of the movements of the wiper block 553. In a like manner, a pipe *g* is connected to the cylinders 75

664, 664, behind the pistons 665, 665 and a pipe *h* is connected to the space behind the inflatable wiper member 660 of the other unit C.

The inflatable wipers 560 and 660 are normally subjected to a relatively low air pressure, approximately six lbs. per square inch. However, after these wipers have been operated to wipe the lasting margin of the tensioned stock, along the opposite sides of the shoe, in over the bottom of the shoe, by means of the pistons 565 and 665, these wipers are inflated to a much higher pressure for pressing the lasting margin of the stock against the shoe bottom.

For supporting the bottom of a shoe being lasted and for preventing displacement or distortion of its sole member, for example, an innersole of the platform sole of a slip-lasted shoe, during the lasting operation, the machine is provided with a sole-engaging presser member 700. This member is formed of sheet metal and, as shown in Figs. 4, 5, 6 and 7, is shaped to correspond to the longitudinal curvature of the sole member. A block 702 is mounted on the table 20, midway between the operating units A, B, C and D, see Figs. 12 and 13, and this block is formed with a chamber 704 that merges into a plurality of cylinders 706 in which are located a plurality of pistons 708. The piston rods 709 of these pistons extend up through the block 702 where they are connected to downwardly extending bosses 710 on the presser member 700, Fig. 7. A flexible air pipe *m* is connected to the chamber 704 and hence to the cylinders 706.

The wipers 380, 460, 560 and 660 of the several operating units are operated to wipe the lasting margin of the stock being lasted and, thereafter, to press the lasting margin of the stock against the bottom of the shoe in definite time relation to the movements of the units A, B, C and D, toward and into operative position relative to the shoe being lasted, and to the vertical movements of the table T. The arrangement for supplying compressed air to the several wiper-operating cylinders and the mechanisms for controlling the flow of air to inflate the wipers will now be described with particular reference to Fig. 1, 2, 17, 18 and 19. To avoid confusion with mechanical structure, the various air pipes have been identified with small letters and this procedure will be continued in the following description.

Referring to Fig. 17, which is a diagrammatic drawing showing the air pressure system and the operating units, a pipe *z* is connected to a suitable source of compressed air, not shown, at a pressure of approximately sixty lbs. per square inch. Connected directly to this supply pipe is a flexible pipe *y* that leads to a pair of solenoid-operated valves 800 and 900. The pipe *z*, beyond the connection with pipe *y*, is connected to a reducing valve 802, set at approximately twenty-eight lbs. per square inch, as indicated by a gage 804 and from this reducing valve the pipe *m* leads to the chamber 704 in the block 702. A pipe *x* leads from the reducing valve 802 to a second reducing valve 806, set for a pressure of approximately twenty lbs. per square inch, as indicated by a gage 808 which is located at the end of a pipe *w*. Leading from the pipe *w* are a pair of pipes *v* and *u* that are connected respectively to three-way valves 810 and 812.

The constructions of these valves 810 and 812 are identical as is diagrammatically illustrated in Fig. 17a. Referring to this figure, in the housing 810 (or 812) is a rotatable plug 814 (or 914)

having a cross passage 818 (or 918). The pipes *l*, *h* are connected to the valve 810, while the pipes *c*, *f* are connected to the valve 812. A low-pressure relief valve 820, set at approximately six lbs. per square inch, is connected to the valve 810 and a similar relief valve 920 is connected to the valve 812. When the valve plug 814 is in the position shown in Fig. 17a, the pressure of the air admitted to the pipes *l*, *h* is maintained at six lbs. per square inch by the relief valve 820. However, if the plug 814 is rotated ninety degrees, the full pressure in pipe *v*, twenty lbs. per square inch, will be admitted to the pipes *l*, *h*. Similarly, by rotating plug 914 of the valve 812, either the low-pressure air at six lbs. per square inch, or the high-pressure air at twenty lbs. per square inch, may be admitted to the pipes *c*, *f*.

The valve plugs 814 and 914 are operated, respectively, by means of cam segments 822 and 922 which are adjustably secured to an arcuate plate 823 on the side of the cam 50, Figs. 18 and 19. Secured to the valve plug 814 is a handle 824 which is connected, by a link 826, to one arm of a bell-crank lever 828. This lever is pivotally mounted on a plate 830, supported on one of the cross members 44, and carries on its other arm a cam roll 832. A coil spring 834, connected to the handle 824, holds this handle in the position shown in Fig. 19 and against a stop 836. Similarly, a handle 924 is connected, by a link 926, to one arm of a bell-crank lever 928 which is likewise pivotally mounted on the plate 830 and provided with a cam roll 932. A spring 934 (Fig. 2) holds the handle 924 in the position shown. The roll 832 is in line with the cam segment 822, while the roll 932 is in line with the cam segment 922.

Located above the rolls 832 and 932 respectively, are microswitches 940 and 840. The microswitch 840 is connected by leads 842, 844 to a main switch 850 and to a solenoid 860 that is arranged to operate the valve 800, while the microswitch 940 is connected by leads 942, 944 to the main switch 850 and to a solenoid 960 for operating the valve 900, Fig. 17. The valve 800 is of the "reversing" type and has a plunger 870 which, in the position shown in Fig. 17, admits compressed air from the pipe *y* to the pipes *b*, *e* while connecting pipes *a*, *d* to exhaust. The plunger 870 is connected to the armature 872 of solenoid 860 by means of a bell-crank lever 874 and a spring 876 is connected to this lever. When the solenoid 860 is energized, by the closing of the switch 840, the plunger 870 will be moved to the left so as to connect the pipes *a*, *b* to the pipe *y* and pipes *b*, *e* to exhaust. The valve 900 is of the "off-on" type and has a plunger 970 which, when in the position shown in Fig. 17, connects the pipes *g*, *k* to exhaust. The plunger 970 is connected to the armature 972 by means of a bell-crank lever 974 and a spring 976 is connected to this lever. When the solenoid 960 is energized, by the closing of the microswitch 940, the plunger 970 will be moved to the left, Fig. 17, so as to connect the pipes *g*, *k* to air pressure from pipe *y*. The switch 850 is connected to a suitable source of electrical energy and also to the motor 78.

A complete operating cycle of the machine will now be described. When the machine is in use, the main switch 850 is closed and the motor 78 running. Also, compressed air from the source is supplied to the pipes *z* and *m*. After a shoe is supplied to the bracket 106, the operator pushes the plunger 86 in, thus tripping the 75. Fig. 13.

clutch 74 for a single revolution of the cam 50, cam segments 822 and 922 carried thereby, and also of cam 120. When the operating cycle has been completed, the clutch 74 is released and shaft 62, which drives the aforementioned cams, brought to a stop in the manner described above. At the beginning of this cycle, the parts are in the positions shown in Fig. 4, with the units A, B, C, D withdrawn, see Figs. 12 and 13, table T in its lowermost position and the presser member 700 elevated as shown in Figs. 3 and 4.

When the cycle starts, the table is elevated to the position shown in Fig. 5, by the action of springs 46, 46 as the roll 48 travels down the rise 52 on cam 50, Fig. 19. As the table is thus elevated, the pressure member engages the bottom of the shoe and the pistons 708 are forced downwardly against the pressure of the air beneath them, which tends to hold the presser member firmly against the bottom of the shoe. Next, the heel and toe units A and B are moved toward and into engagement with the heel and toe ends of the shoe, as shown in Fig. 6, as the rise 121 on cam 120 engages the roll 160, Fig. 13. With the units A and B in these positions and with the flexible bands 312, 412 snugly embracing the heel and toe ends of the shoe, the table now moves downwardly, a short distance, as the roll 48 travels up the rise 56 on the cam 50. During this downward movement of the table, the stock being lasted, herein illustrated as the wrapper W of a platform shoe, is tensioned in a direction heightwise of the last by the frictional drag that is imposed on it by the tread surfaces 314, 414 of the flexible rubber bands 312, 412, associated with the units A and B.

While the table remains in this partially lowered position, the heel and toe wipers 360, 460 are operated to wipe the lasting margin of the tensioned wrapper W in over the toe and heel ends of the shoe; this action occurring when the switch 840 is closed by the cam segment 922 thus connecting the pipes *a* and *d* to air pressure from the pipe *y* and connecting pipes *b* and *e* to exhaust so that pistons 366 and 466 are actuated, see Figs. 7 and 8, for the action of the heel wiper 360 and toe wiper 460. During this action, the wipers 360, 460 are inflated at a relatively low pressure of six lbs. per square inch, as determined by the relief valve 920, and, therefore, readily conform to the marginal edge of the bottom of the shoe. However, immediately thereafter, the cam segment 922 engages the roll 932, thus rotating the valve plug 914 so as to inflate the wipers 360, 460 with air at twenty lbs. per square inch. When thus inflated, the wipers 360, 460 press the overwiped lasting margin of the wrapper W firmly against the platform P and heel part H. It will be understood that the wrapper and/or the platform and heel part will have previously been coated with a suitable adhesive so that the lasting margin of the wrapper is securely bonded to the platform and to the heel end by the pressure applied by the wipers 360, 460. As cam segment 922 passes by the switch 840 and the roll 932, the wipers 360, 460 are deflated to the low pressure of six lbs. per square inch and withdrawn almost simultaneously, when valve plug 914 is returned to its original position so as to connect pipes *a* and *d* to exhaust and pipes *b* and *e* to air pressure from pipe *y*. The first half of the cycle is completed when the toe and heel units are retracted as the roll 160 rides down onto the dwell 123 of cam 120, 75. Fig. 13.

At the beginning of the second half of the cycle, the table T is again elevated to the position shown in Fig. 5, by springs 46, 46, as roll 48 rides down onto the drop 58 of the cam 50, Fig. 19. The side units C and D are now moved toward and into engagement with the opposite sides of the shoe, as shown in Figs. 11 and 15, when the roll 203 rides up onto the rise 121 on the cam 120, Fig. 13. Next, the table is lowered when the roll 48 rides up onto the rise 60 on cam 50. As the table is thus moved downwardly, the wrapper W, at the opposite sides of the shoe, is tensioned in a heightwise direction by the frictional drag imposed upon it by the tread surfaces 514, 614 of the bands 513, 613, associated with the side units C and D, which snugly embrace the last at the opposite side of the shoe.

While the table remains in this partially lowered position, the wipers 560, 660, inflated at the low pressure of six pounds per square inch, are operated to wipe the lasting margin of the tensioned wrapper in over the bottom of the shoe at its opposite sides, this action occurring when switch 949 is closed by the cam segment 822, thus connecting pipes g, k to air pressure from pipe y to operate the pistons 565 and 665. Immediately thereafter, the wipers 560, 660 are inflated to the high pressure of twenty lbs. per square inch when the segment 822 engages the roll 832, thus rotating the plug 814 of valve 810. The wipers 560, 660 now press the lasting margin of the wrapper firmly against the platform P at the opposite sides of the shoe. When the cam segment 822 passes by the switch 949 and the roll 832, the side wipers 560, 660 are deflated to the low pressure of six lbs. per square inch, as determined by the relief valve 820 and withdrawn by springs 559, 659, after which, the side units C and D are retracted to their original positions by spring 202. Finally, as the roll 48 rides up the rise 52 on the cam 50, the table is lowered to its initial position, see Fig. 4, and the operating cycle is completed as the clutch 74 is released and the shaft 62 brought to a stop.

During the downward movements of the table, when the stock being lasted is tensioned by the frictional action of the bands 312, 412, or 513, 613, the presser foot 700 is at all times firmly held against the platform P and heel portion H by means of the compressed air beneath the pistons 708, 708, these pistons rising and falling in the manner illustrated in Figs. 7 and 8.

Because of the inherent flexibility and conformability of the tensioning bands 312, 412, 513 and 613 and also of the wiping elements 360, 460, 560 and 660, the herein illustrated machine will readily accommodate itself to shoes of widely varying shapes. Also, the machine may be set to last shoes of different sizes by loosening the four clamp bolts 132, 142, 172 and 182 and shifting the positions of brackets 130, 140, 170 and 180 with respect to blocks 134, 136, 144, 146, 174, 176 and 184, 186. If desired, suitable pointers and size indicia may be provided on these brackets and blocks to facilitate these settings. The frictional action of the flexible bands 312, 412, 513 and 613, augmented by the tread surfaces 314, 414, 514 and 614 formed thereon, is wholly adequate to tension the stock being lasted whether it be the wrapper W of a platform shoe, as herein illustrated, or the upper of a conventional shoe. Also, in either case, the wiping members 360, 460, 560 and 660 not only lay the lasting margin of the stock smoothly in over the bottom of the shoe, regardless of the edge curvature, due to the con-

formable character of these wipers, but also press it very firmly against the bottom of the shoe when inflated at the higher air pressure. Moreover, all of these actions occur automatically and without the need of any assistance from the operator after the shoe to be lasted has been secured to the bracket 106 and the clutch-controlling plunger 86 pushed inwardly.

Because of the aforementioned automatic action, the herein illustrated machine is particularly well adapted for use in connection with a conveyor system, or the like. As will be readily understood by persons skilled in the art, the shoes to be lasted could be conveniently transported to and from the machine by means of a conveyor, or similar mechanism, provided with a plurality of lasts or shoe forms, and arranged not only so as to position the shoes on these lasts, or forms, successively in a proper location between the lasting units A, B, C and D, during the operation of these units, but also to operate the plunger 86 for controlling the operation of the machine in time relation to the movements of the conveyor.

While the machine has been herein illustrated as operating on the wrapper W of a slip-lasted shoe, it is to be understood, as already suggested above, that the machine is not limited to use on work of this kind. Instead, and as well be apparent, the units A, B, C and D, possibly with slight changes in the heightwise positions of the flexible bands and the wipers, would be equally well adapted for tensioning, overlaying and pressing the upper of a conventional shoe. Therefore, in the following claims the expression "stock being lasted" is intended to refer not only to the wrapper of a slip-lasted shoe but also to the upper of a conventional shoe. Also, if for any reason it is desired to last either the heel and toe ends or the opposite sides of the shoe in some manner, the corresponding units A, B or C and D may be rendered inoperative, by disconnecting their respective operating mechanisms, or, if preferred, entirely removed from the table, without in any respect detracting from the utility of the retained units.

Having described the invention, what is claimed as new and desired to be secured by Letters Patent of the United States is:

1. A lasting machine having, in combination, a support for a shoe on its last, a plurality of different lasting units for operating on different portions of a shoe carried by said support, each of said units comprising a member conformable to the contour of the last and operable, upon movement relative to the last, to tension the stock being lasted in a direction heightwise of the last and a wiping means, movable relatively to the conformable member for laying the lasting margin of the tensioned stock inwardly over, and for pressing said lasting margin against, the bottom of the shoe, and means for operating said different units in a predetermined sequence to effect the lasting of different portions of the shoe around its entire periphery.

2. A lasting machine having, in combination, a support for a shoe on its last, a pair of lasting units for operating, respectively, on the toe and heel ends of a shoe carried by said support, a pair of lasting units for operating, respectively, on the opposite sides of said shoe, each of said units comprising a member conformable to the contour of the last and operable, upon movement relative to the last, to tension the stock being lasted in a direction heightwise of the last and

a wiping member movable relatively to the conformable member for laying the lasting margin of the tensioned stock in over, and for pressing said lasting margin against, the bottom of the shoe, and means for operating said different pairs of units in a predetermined sequence to effect lasting of the stock at the toe and heel ends and along the opposite sides of the shoe.

3. A lasting machine having, in combination, a support for a shoe on its last, a plurality of different lasting units for operating on different portions of a shoe carried by said support, each of said units comprising a member conformable to the contour of the last and operable, upon movement relative to the last, to tension the stock being lasted in a direction heightwise of the last, and wiping means including a member conformable to the marginal edge of the bottom of the shoe for laying the lasting margin of the tensioned stock inwardly, and for pressing said lasting margin against, the bottom of the shoe, and means for operating said different units in a predetermined sequence to effect lasting of different portions of the shoe around its entire periphery.

4. A lasting machine having, in combination, a support for a shoe on its last, a pair of lasting units for operating, respectively, at the toe and heel ends of a shoe carried by said support, a pair of lasting units for operating, respectively, on the opposite sides of said shoe, each of said units comprising a member conformable to the contour of the last and operable, upon movement relative to the last, to tension the stock being lasted in a direction heightwise of the last, and wiping means including a member conformable to the marginal edge of the bottom of the shoe for laying the lasting margin of the tensioned stock inwardly over, and for pressing said lasting margin against, the bottom of the shoe, and means for operating said different pairs of units in a predetermined sequence to effect lasting of the stock at the toe and heel ends and along the opposite sides of the shoe.

5. A lasting machine having, in combination, a support for a shoe on its last, a plurality of different lasting units for operating on different portions of a shoe carried by said support, each of said units comprising a member conformable to the contour of the last and operable, upon movement relative to the last, to tension the stock being lasted in a direction heightwise of the last, and wiping means including an inflatable member, conformable to the marginal edge of the bottom of the shoe, for laying the lasting margin of the tensioned stock inwardly over, and for pressing said lasting margin against, the bottom of the shoe, and means for operating said different units in a predetermined sequence to effect lasting of different portions of the shoe around its entire periphery.

6. A lasting machine having, in combination, a support for a shoe on its last, a pair of lasting units for operating, respectively, at the toe and heel ends of a shoe carried by said support, a pair of lasting units for operating, respectively, along the opposite sides of the shoe, each of said units comprising a member conformable to the contour of the last and operable, upon movement relatively to the last, to tension the stock being lasted in a direction heightwise of the last, and wiping means including an inflatable member, conformable to the marginal edge of the bottom of the shoe, for laying the lasting margin of the tensioned stock inwardly over, and for pressing the overlaid lasting margin against the bottom of the shoe, and means for inflating said inflatable member at

said lasting margin against, the bottom of the shoe, and means for operating said different pairs of units in a predetermined sequence to effect lasting of the stock, at the toe and heel ends and along the opposite sides of the shoe.

7. A lasting machine having, in combination, a support for a shoe on its last, a pair of lasting units for operating, respectively, on the opposite sides of a shoe carried by said support, each of said units comprising a member conformable to the contour of the last and operable upon movement relative to the last, to tension the stock being lasted in a direction heightwise of the last, and wiping means including an inflatable member, conformable to the marginal edge of the bottom of the shoe, for laying the lasting margin of the tensioned stock inwardly over, and for pressing said lasting margin against, the bottom of the shoe, and means for operating said units to effect lasting of the stock along the opposite sides of the shoe.

8. A lasting machine having, in combination, a support for a shoe on its last, a pair of lasting units for operating, respectively, at the toe and heel ends of a shoe carried by said support, each of said units comprising a member conformable to the contour of the last and operable, upon movement relative to the last, to tension the stock being lasted in a direction heightwise of the shoe, and wiping means including an inflatable member, conformable to the marginal edge of the bottom of the shoe, for laying the lasting margin of the tensioned stock inwardly over and for pressing said lasting margin against, the bottom of the shoe, and means for operating said units to effect lasting of the stock at the toe and heel ends of the shoe.

9. A lasting machine having, in combination, a support for a shoe on its last, a plurality of different lasting units for operating on different portions of a shoe carried by said support, each of said units comprising a member conformable to the contour of the last and operable, upon movement relative to the last, to tension the stock being lasted in a direction heightwise of the last, wiping means including an inflatable member, conformable to the marginal edge of the bottom of the shoe, for laying the lasting margin of the tensioned stock inwardly over, and for pressing said lasting margin against, the bottom of the shoe, and means for inflating said inflatable member at a relatively low pressure during its overlaying action and thereafter at a higher pressure for pressing the overlaid lasting margin against the bottom of the shoe, and means for operating said different units in a predetermined sequence to effect lasting of different portions of the shoe around its entire periphery.

10. A lasting machine having, in combination, a support for a shoe on its last, a plurality of different lasting units for operating on different portions of a shoe carried by said support, each of said units comprising a member conformable to the contour of the last and operable, upon movement relative to the last, to tension the stock being lasted in a direction heightwise of the last, wiping means including an inflatable member, conformable to the marginal edge of the bottom of the shoe and movable relatively to the first-mentioned conformable member, for laying the lasting margin of the tensioned stock in over, and for pressing the overlaid lasting margin against the bottom of the shoe, and means for inflating said inflatable member at

a relatively low pressure during its overlaying action and thereafter at a higher pressure for pressing the overlaid lasting margin against the bottom of the shoe, and means for operating said different units in a predetermined sequence to effect lasting of different portions of the shoe around its entire periphery.

11. A lasting machine having, in combination, a support for a shoe on its last, a pair of lasting units for operating, respectively, on the toe and heel ends of a shoe carried by said support, a pair of lasting units for operating, respectively, on the opposite sides of said shoe, each of said units comprising a member conformable to the contour of the last and operable, upon movement relative to the last, to tension the stock being lasted in a direction heightwise of the last, wiping means including an inflatable member, conformable to the marginal edge of the bottom of the shoe, for laying the lasting margin of the tensioned stock inwardly over, and for pressing said lasting margin against, the bottom of the shoe, and means for inflating said inflatable member at a relatively low pressure during its overlaying action and thereafter at a higher pressure for pressing the overlaid lasting margin against the bottom of the shoe, and means for operating said different pairs of units in a predetermined sequence to effect the lasting of the shoe around its entire periphery.

12. A lasting machine having, in combination, a support for a shoe on its last, a pair of lasting units for operating, respectively, on the toe and heel ends of a shoe carried by said support, a pair of lasting units for operating, respectively, on the opposite sides of said shoe, each of said units comprising a member conformable to the contour of the last and operable, upon movement relative to the last, to tension the stock being lasted in a direction heightwise of the last, wiping means including an inflatable member, conformable to the marginal edge of the bottom of the shoe and movable relatively to the first-mentioned conformable member, for laying the lasting margin of the tensioned stock in over, and for pressing the overlaid lasting margin against, the bottom of the shoe, and means for inflating said inflatable member at a relatively low pressure during its overlaying action and thereafter at a higher pressure for pressing the overlaid lasting margin against the bottom of the shoe, and means for operating said different pairs of units in a predetermined sequence to effect the lasting of the shoe around its entire periphery.

13. A lasting machine having, in combination, a support for a shoe on its last, a pair of lasting units for operating, respectively, on the opposite sides of a shoe carried by said support, each of said units comprising a member conformable to the contour of the last and operable, upon movement relative to the last, to tension the stock being lasted in a direction heightwise of the last, wiping means including an inflatable member, conformable to the marginal edge of the bottom of the shoe, for laying the lasting margin of the tensioned stock inwardly over, and for pressing said lasting margin against, the bottom of the shoe, and means for inflating said inflatable member at a relatively low pressure during its overlaying action and thereafter at a higher pressure for pressing the overlaid lasting margin against the bottom of the shoe, and means for operating said units to effect the lasting of the stock along the opposite sides of the shoe.

14. A lasting machine having, in combination, a support for a shoe on its last, a plurality of lasting units for operating, respectively, on the opposite sides of a shoe carried by said support, each of said units comprising a member conformable to the contour of the last and operable, upon movement relative to the last, to tension the stock being lasted in a direction heightwise of the last, wiping means including an inflatable member, conformable to the marginal edge of the bottom of the shoe and movable relatively to the first-mentioned conformable member, for laying the lasting margin of the tensioned stock in over, and for pressing the overlaid lasting margin against, the bottom of the shoe, and means for inflating said inflatable member at a relatively low pressure during its overlaying action and thereafter at a higher pressure for pressing the overlaid lasting margin against the bottom of the shoe, and means for operating said units to effect the lasting of the stock along the opposite sides of the shoe.

15. A lasting machine having, in combination, a support for a shoe on its last, a pair of lasting units for operating, respectively, at the toe and heel ends of a shoe carried by said support, each of said units comprising a member conformable to the contour of the last and operable, upon movement relative to the last, to tension the stock being lasted in a direction heightwise of the last, wiping means including an inflatable member, conformable to the marginal edge of the bottom of the shoe, for laying the lasting margin of the tensioned stock inwardly over, and for pressing said lasting margin against, the bottom of the shoe, and means for inflating said inflatable member at a relatively low pressure during its overlaying action and thereafter at a higher pressure for pressing the overlaid lasting margin against the bottom of the shoe, and means for operating said units to effect the lasting of the stock at the toe and heel ends of the shoe.

16. A lasting machine having, in combination, a support for a shoe on its last, a pair of lasting units for operating, respectively, at the toe and heel ends of a shoe carried by said support, each of said units comprising a member conformable to the contour of the last and operable, upon movement relative to the last, to tension the stock being lasted in a direction heightwise of the last, wiping means including an inflatable member, conformable to the marginal edge of the bottom of the shoe and movable relatively to the first-mentioned conformable member, for laying the lasting margin of the tensioned stock in over, and for pressing the overlaid lasting margin against, the bottom of the shoe, and means for inflating said inflatable member at a relatively low pressure during its overlaying action and thereafter at a higher pressure for pressing the overlaid lasting margin against the bottom of the shoe, and means for operating said units to effect lasting of the stock at the toe and heel ends of the shoe.

17. A lasting machine having, in combination, a support for a shoe on its last, means for tensioning the stock being lasted along a selected portion of the shoe, and wiping means comprising an inflatable member, conformable to the marginal edge of the bottom of the shoe at said selected portion and bodily movable relatively to said tensioning means, for laying the lasting margin of the tensioned stock inwardly over, and

for pressing said lasting margin against, the bottom of the shoe.

18. A lasting machine having, in combination, a support for a shoe on its last, means for tensioning the stock being lasted along a selected portion of the shoe, wiping means comprising an inflatable member, conformable to the marginal edge of the bottom of the shoe at said selected portion and bodily movable relatively to the tensioning means, for laying the lasting margin of the tensioned stock inwardly over, and for pressing said lasting margin against, the bottom of the shoe, and means for inflating said inflatable member at a relatively low pressure during its overlaying action and thereafter at a higher pressure for pressing the overlaid lasting margin against the bottom of the shoe.

19. A lasting machine having, in combination, a support for a shoe on its last, means for tensioning the stock being lasted at an end portion of said shoe, and wiping means comprising an inflatable member, conformable to the marginal edge of the bottom of the shoe at said end portion and bodily movable relatively to said tensioning means, for laying the lasting margin of the tensioned stock inwardly over, and for pressing said lasting margin against, the bottom of the shoe.

20. A lasting machine having, in combination, a support for a shoe on its last, means for tensioning the stock being lasted at an end portion of said shoe, and wiping means comprising an inflatable member, conformable to the marginal edge of the bottom of the shoe at said end portion and bodily movable relatively to the tensioning means, for laying the lasting margin of the tensioned stock inwardly over, and for pressing said lasting margin against, the bottom of the shoe, and means for inflating said inflatable member at a relatively low pressure during its overlaying action and thereafter at a higher pressure for pressing the overlaid lasting margin against the bottom of the shoe.

21. A lasting machine having, in combination, a support for a shoe or its last, means for tensioning the stock being lasted along a selected portion of the side of said shoe, and wiping means comprising an inflatable member, conformable to the marginal edge of the bottom of the shoe at said selected portion and bodily movable relatively to said tensioning means, for laying the lasting margin of the tensioned stock inwardly over, and for pressing said lasting margin against, the bottom of the shoe.

22. A lasting machine having, in combination, a support for a shoe on its last, means for tensioning the stock being lasted along a selected portion of the side of said shoe, and wiping means comprising an inflatable member, conformable to the marginal edge of the bottom of the shoe at said selected portion and bodily movable relatively to the tensioning means, for laying the lasting margin of the tensioned stock inwardly over, and for pressing said lasting margin against, the bottom of the shoe, and means for inflating said inflatable member at a relatively low pressure during its overlaying action and thereafter at a higher pressure for pressing the overlaid lasting margin against the bottom of the shoe.

23. A lasting machine having, in combination, a support for a shoe on its last, a table mounted for reciprocation relative to a shoe carried by said support, a plurality of different lasting units for

operating on different portions of the shoe, each of said units being mounted on said table for movement toward and away from operative position relative to the shoe and including means for tensioning the stock being lasted in a direction heightwise of the last, at a selected portion of the shoe, and wiping means for laying the lasting margin of the tensioned stock inwardly over, and for pressing said lasting margin against, the bottom of the shoe, and power-operated means for reciprocating said table and for moving and operating said different lasting units in a predetermined sequence to effect lasting of different portions of the shoe around its entire periphery.

24. A lasting machine having, in combination, a support for a shoe on its last, a table mounted for reciprocation relative to a shoe carried by said support, a pair of lasting units for operating, respectively, on the toe and heel ends of the shoe, a pair of lasting units for operating, respectively, on the opposite sides of the shoe, each of said units being mounted on said table for movement toward and away from operative position relative to the shoe and including means for tensioning the stock being lasted in a direction heightwise of the last, at a selected portion of the shoe, and wiping means for laying the lasting margin of the tensioned stock inwardly over, and for pressing said lasting margin against, the bottom of the shoe, and power-operated means for reciprocating said table and for moving and operating said different pairs of lasting units in predetermined sequence to effect lasting of the shoe around its entire periphery.

25. A lasting machine having, in combination, a support for a shoe on its last, a table mounted for reciprocation relative to a shoe carried by said support, a pair of lasting units for operating, respectively, at the toe and heel ends of the shoe, each of said units being mounted on said table for movement toward and away from operative position relative to the shoe and including means for tensioning the stock being lasted in a direction heightwise of the last, at a selected portion of the shoe, and wiping means for laying the lasting margin of the tensioned stock inwardly over, and for pressing said lasting margin against, the bottom of the shoe, and power-operated means for reciprocating said table and for moving and operating said units to effect lasting of the stock at the toe and heel ends of the shoe.

ERNEST W. STACEY.
DANIEL WALKER HANNABLE.
